US0D1094537S

(12) **United States Design Patent** (10) **Patent No.:** **US D1,094,537 S**
(45) **Date of Patent:** **** Sep. 23, 2025**

(54) **TYPE FONT**(71) Applicant: **Apple Inc.**, Cupertino, CA (US)(72) Inventors: **Guillaume P. Barlier**, Sunnyvale, CA (US); **Alan C. Dye**, San Francisco, CA (US); **Aurelio Guzmán**, San Jose, CA (US); **Nicolas V. Scapel**, London (GB); **Christopher I. Wilson**, San Francisco, CA (US)(73) Assignee: **Apple Inc.**, Cupertino, CA (US)(**) Term: **15 Years**(21) Appl. No.: **29/920,403**(22) Filed: **Dec. 11, 2023****Related U.S. Application Data**

(63) Continuation of application No. 29/764,065, filed on Dec. 28, 2020, now Pat. No. Des. 1,007,574, which is a continuation of application No. 29/688,488, filed on Apr. 22, 2019, now Pat. No. Des. 907,110, which is a continuation of application No. 29/649,901, filed on Jun. 3, 2018, now Pat. No. Des. 846,633.

(51) **LOC (15) Cl.** **18-03**(52) **U.S. Cl.**USPC ..... **D18/33; D14/492; D14/494; D18/27**(58) **Field of Classification Search**USPC D14/492, 494; D18/24-28, 32, 33
CPC G09B 11/00; G09B 11/04; G09B 17/00;
